UNITED STATES PATENT OFFICE

117,947

DESIGN FOR A HANDBAG

Sigmund Dawer, New York, N. Y.

Application April 21, 1939, Serial No. 84,445

Term of patent 3½ years

To all whom it may concern:

Be it known that I, Sigmund Dawer, a citizen of the United States of America, residing in New York city, in the Borough of Manhattan, county and State of New York, have invented a new, original, and ornamental Design for a Handbag, of which the following is a specification, reference being had to the accompanying drawing, forming part thereof, wherein:

The rear of the handbag is substantially the same as the front.

The characteristic feature of my design resides in the specific superimposed bead embroidery on the handbag as shown.

I claim:

The ornamental design for a handbag, substantially as shown and described.

SIGMUND DAWER.
